UNITED STATES PATENT OFFICE.

CARL GUSTAVE GRONQUIST, OF BRIDGEPORT, CONNECTICUT, ASSIGNOR, BY MESNE ASSIGNMENTS, TO THE LOCOMOBILE COMPANY, OF BRIDGEPORT, CONNECTICUT, A CORPORATION OF DELAWARE.

OILING DEVICE.

1,356,355.

Specification of Letters Patent. Patented Oct. 19, 1920.

Application filed December 8, 1917. Serial No. 206,174.

To all whom it may concern:

Be it known that I, CARL GUSTAVE GRONQUIST, a subject of the King of Sweden, (who have declared my intention of becoming a citizen of the United States,) and a resident of Bridgeport, county of Fairfield, and State of Connecticut, have invented an Improvement in Oiling Devices, of which the following description, in connection with the accompanying drawings, is a specification, like characters on the drawings representing like parts.

10 This invention relates to oiling devices, and is more especially, though not exclusively, concerned with means to clear away accumulation of dust, dirt and other foreign matter preparatory to the introduction of the oil, so that no foreign matter shall be carried into the oil passage.

15 My invention will be best understood by reference to the following description, when taken in connection with the accompanying drawings of two illustrative embodiments thereof, while its scope will be more particularly pointed out in the appended claims.

20 In the drawings:

Figure 1 is a plan of an oiling device embodying my invention, showing the same as it appears when closed;

30 Fig. 2 is a plan of the same showing the device as it appears when open for the introduction of oil;

Fig. 3 is a sectional view on line 3—3 of Fig. 2;

35 Fig. 4 is a sectional view on line 4—4 of Fig. 3;

Fig. 5 is a plan of another form of oiling device embodying my invention, showing the same as it appears when closed;

40 Fig. 6 is a plan of the same as it appears when open; and

Fig. 7 is a sectional view on line 7—7 of Fig. 6.

45 Referring to the drawings, and to the embodiment of my invention which is illustrated in Figs. 1 to 4, inclusive, I have there shown an oiling device comprising two relatively movable parts 8 and 9, having normally non-registering openings 10 and 11, which may be brought into registration to permit the introduction of oil therethrough into a passage 12, which may be, and in the present example is, a chamber or reservoir for supplying oil through a passage 13 to a bearing surface 14. It should be under-

stood, however, that my invention is by no means limited to an oiling device of any particular class or to the lubrication of bearings of any particular kind, but that it is susceptible of very general application.

60 The part 8 may be mounted to move in any suitable manner on the part 9, but in the present example is mounted to turn thereon, and is arranged co-axially with relation thereto. The outer opening 10 is elongated in the direction of travel, as best shown in Figs. 2 and 4, and is formed substantially concentric with the common axis of the parts 8 and 9. I may provide any suitable means movable lengthwise of the elongated opening 10 to clear the latter of foreign matter preparatory to the introduction of the oil, but in the present example, I have shown a pin 15 secured to the part 9 and projecting into said slot. In the present instance, this pin is snugly fitted into a hole 16 in the inner part 9, and, as an additional measure of precaution, to prevent the pin from being dislodged, I have herein provided the same with lateral indentations 17, into which spurs 18, formed of the metal of the surrounding part 9, may be driven by a suitable implement, thereby to interlock with the pin and prevent the same from dropping out.

85 If now, when the device is closed, there are any accumulations of dust, dirt or other foreign matter in the outer opening 10, when the outer part 8 is turned to expose the inner opening 11 for the introduction of oil, the pin 15 will traverse the outer opening and clear such opening of the accumulation of foreign matter, so that there will be no danger of its entering the opening 11. The pin 15 performs two other functions,—first, it co-operates with the slot 10 to limit the relative movement of the parts 8 and 9; and second, it prevents separation of said parts.

95 If desired, there may be provided suitable means tending to resist turning movement of one part upon the other, and in the present example, I have shown for this purpose a spring 19 bearing at one end against the inner face of the outer part 8. The other end of this spring bears against a cap 20, which closes the outer end of the passage 12. This spring tends to urge the part 8 in an outward direction on the part 9, and since such movement is prevented by the pin 15,

the friction of these parts one on the other serves as an effective means for preventing accidental opening of the device.

The form of my invention hereinbefore described is particularly adapted for horizontal arrangement, but the form shown in Figs. 5, 6 and 7, is especially adapted for use in an upright position. Referring to the latter form, I have shown an oiling device comprising outer and inner parts 21, and 22, arranged to turn one on the other, and provided with normally non-registering openings 23 and 24, which may be brought into registration to permit the introduction of oil therethrough. In this form, the oil is introduced through these openings into a chamber 25, constituting a reservoir formed in a separate part 26 onto which the part 22 is threaded. A stand-pipe 27 mounted in the part 26 and extending into the reservoir receives oil from the latter by means of a wick 28, which feeds the oil by capillary action to passages 29 and 30, by means of which it is delivered to a bearing surface 31. It should now be apparent that the inner opening 24 is normally closed by the outer part 21, as shown in Fig. 5, and that when the latter is turned to the position shown in Fig. 6, the openings 23 and 24 are brought into registration, and in so doing a pin 32 secured to the inner part and projecting into the opening in the outer part clears such opening of any accumulations of foreign matter, and prepares the openings for the introduction of the oil. In this form, the pin serves also as a means for limiting relative turning movement of the parts 21 and 22. Separation of these parts, however, in this example is prevented by a suitable fastening element, preferably in the form of a rivet 33 which passes axially through the parts 21 and 22, as best shown in Fig. 7, and thus prevents accidental separation of these parts.

While I have herein shown and described two specific forms or embodiments of my invention, and have disclosed and discussed in detail the construction and arrangement incidental to two specific applications thereof, it is to be understood that the invention is limited neither to the mere details or relative arrangements of parts, nor to its specific embodiments therein shown, but that extensive deviations from the illustrated forms or embodiments of the invention may be made, without departing from the principles thereof.

Having thus described my invention, what I claim and desire by Letters Patent to secure is:

1. In an oiling device, the combination of inner and outer relatively-rotatable co-axially-arranged parts having normally non-registering openings which may be brought into registration for the introduction of oil,

the opening in the outer part being elongated and formed substantially concentric with the common axis of said parts, said inner part presenting a reservoir entirely therein, and means carried by the inner part adapted to traverse such elongated opening to clear the same of foreign matter preparatory to the introduction of oil. 70

2. In an oiling device, the combination of an inner part provided with an oil passage 75 and an opening communicating therewith, an outer part comprising a cup-like cap having a sleeve portion encircling and mounted to turn on the outside of said inner part and provided with a circumferentially elongated 80 opening, which in one position of said sleeve registers with the opening in said inner part and in another position is out of registration therewith, and means on said inner part projecting into said elongated opening and 85 traversing the latter when said cap is turned to carry said elongated opening into and out of registration with the opening in said inner part.

3. In an oiling device, the combination of 90 an inner part provided with an oil passage and an opening communicating therewith, an outer part comprising a cup-like cap having a sleeve portion encircling and mounted to turn on said inner part and provided with a circumferentially elongated 95 opening, which in one position of said sleeve registers with the opening in said inner part and in another position is out of registration therewith, and means on said inner part projecting into said elongated opening and 100 traversing the latter when said sleeve is turned to carry said elongated opening into and out of registration with the opening in said inner part, said means also limiting the 105 turning movement of said cap and preventing said cap from being withdrawn from said inner part.

4. In an oiling device, the combination of 110 inner and outer relatively movable parts having normally non-registering openings which may be brought into registration to permit the introduction of oil therethrough into the inner part, said outer part comprising a cup-like cap mounted to turn on the 115 inner part, said openings, when registering, providing a passage extending transverse to the direction of their relative movement, the outer opening being elongated in the direction of such movement, and means carried by the inner part to clear said elongated 120 opening of foreign matter preparatory to the introduction of the oil, said means being normally positioned at one end of said elongated opening and having a movement there- 125 in substantially equal in extent to the spacing of said means and said inner opening.

In testimony whereof I have signed my name to this specification.

GUSTAVE GRONQUIST.
